UNITED STATES PATENT OFFICE.

NAFORD B. SANDVIG, OF GRAFTON, NORTH DAKOTA.

GRAIN SEPARATOR.

Application filed December 21, 1925. Serial No. 76,760.

This invention relates to new and useful improvements in separators, and particularly to devices for separating or grading grain seeds.

5 One object of the invention is to provide a device of this character by means of which certain seeds may be efficiently separated from other seeds.

Another object is to provide a novel form 10 of separating drum, by means of which seeds are properly graded, and the desired seeds delivered at one point, while the remainder are delivered at another point.

Another object is to provide a device of 15 this character which includes means for imparting intermittent jerking movements to the separating drum during the rotary movement of the drum.

Other objects and advantages will be apparent from the following description when taken in connection with the accompanying drawings.

In the drawings:

Figure 1 is a side elevation of a grain 20 separating machine made in accordance with the present invention.

Figure 2 is a detail perspective view of the lower portion of the machine, showing the vibrating chute, and operating means 30 therefor.

Figure 3 is an end elevation of the machine, showing the means for producing the jerking motion to the drum.

Figure 4 is an enlarged vertical sectional 35 view on the line 4—4 of Figure 3.

Figure 5 is an elevation of the notched wheel of the drum shaft.

Figure 6 is a side elevation of same.

Figure 7 is a side elevation of the loose 40 bevel gear of the drum shaft.

Figure 8 is a front elevation, or face view, of the loose bevel gear.

Figure 9 is a vertical transverse sectional view on the line 9—9 of Figure 4.

45 Figure 10 is a fragmentary detail sectional view of a portion of the screen drum, showing the interlocking of the rings and strips.

Referring particularly to the accompanying drawings, 10 represents a suitable frame 50 having the hopper 11 mounted in its upper portion, said hopper being provided with a discharge spout 12. In the opposite ends of the frame, and at different levels, are mounted the cross members 13 and 14, respectively, and carried by said members are

the bearing brackets 15, for rotatably supporting the shafts 16 of the ends of the separating drum 17. On the sides of the end of the frame, adjacent ends of the cross member 13, are the bearing brackets 18 in which are supported the ends of the transverse shaft 19, said shaft having on one end the large drive sprocket wheel 20, and the bevel gear 21, to which reference will be made 60 later herein. The sprocket wheel 20 is provided with a crank handle 22, which is grasped to rotate the same.

In the lower portion of the frame, beneath the drum, is a transverse crank shaft 23, 70 and fixed on one end of this shaft is a small sprocket wheel 24, a drive chain 25 engaging around the sprockets 20 and 24. Secured at their lower ends to the other end of the frame are the upwardly extending 75 spring arms 26, and secured to the upper ends of said arms is the upper end of the downwardly and forwardly inclined chute 27, the upper end of said chute being disposed directly beneath the lower rear end 80 of the drum, to receive seeds therefrom and convey same to the front of the machine. Connected to the cranks of the crank shaft 23, and to the lower forward end of the chute 27, are the links 28. 85

The drum comprises an outer imperforate cylinder 29, within which is disposed a reticulated cylinder 30, the latter being spaced from the former. The inner cylinder is made up of the plurality of regularly spaced 90 flat rings 31, the inner edge faces of which are formed with regularly spaced notches 32, receiving the correspondingly notched strips 33, which are thereby spaced at distances equal to the distances between the 95 rings. Rings 34, of slightly smaller diameter than the rings 31, are placed within the inner cylinder to hold the strips in place, a narrow ring 34 being placed at the upper end of the drum, while a wider one 34' 100 is placed at the lower end thereof, said wider ring being projected a suitable distance beyond the lower end of the outer imperforate cylinder 29. It will be noted that the lower end of the outer cylinder 29 lies 105 in position to discharge onto the upper end of the chute 27. On the periphery of certain of the rings 31 are formed the lugs 35, which engage with the inner face of the outer cylinder, to hold the same in proper spaced 110 relation to the inner cylinder, and thereby provide a space, between the cylinders for

the smaller seeds to pass, which have escaped through the meshes of the inner cylinder. The larger seeds pass out from the lower end of the inner cylinder, and are received in any suitable receptacle placed thereunder.

On the upper end of the shaft 16 of the drum is secured a wheel 36, in the periphery of which are formed the series of regularly spaced notches 37. On the outer face 10 of this wheel 36 are formed the pair of lugs 38, and the eye 39. Loosely mounted on the shaft 16, outwardly of the wheel 36, is a bevel gear 40, and on the inner face of said wheel is formed a single lug 41, which is 15 disposed between the lugs 38, and an eye 42. A coil spring 43 has its opposite ends secured in the eyes 39 and 42. The hub 44, of the wheel 36 engages with the face of the bevel gear 40, whereby to hold the wheels 20 in proper spaced relation, and prevent binding of the lugs and spring. On a second cross member 45, on the front end of the frame, immediately above the cross member 13, is mounted a bracket 46, and pivotally 25 supported, at one end, in this bracket is an arm 47, the free end of which overlies the periphery of the notched wheel 36, and rotatably supports a spoked wheel 48. The outer ends of the spokes of the wheel 48 engage in the notches of the wheel 36. On the cross member 13 is a hook 49, and disposed 30 vertically through the arm 47, is a hook 50, the upper end of which is threaded and has a winged nut 51 engaged thereon. A coil spring 52 has its ends engaged with the hooks 49 and 50, for urging the arm downwardly for the purpose of insuring firm 35 contact of the spokes of the wheel 48 with the notched wheel. The winged nut 51 permits adjusting the tension of the coil 40 spring 52. The before-mentioned bevel gear 21 meshes with the bevel gear 40.

Upon turning the sprocket wheel 20 the shaft 19, at the upper end of the drum 17 45 will be rotated, and its bevel gear 21 turn the bevel gear 40 until the lug 41 engages with one of the lugs 38, which causes the gear 40 to turn the shaft 16, and the notched wheel 36. The rotation of the notched 50 wheel causes the drum to be rotated, and at the same time the spokes of the wheel 48 will engage in the notches of the wheel 36. The tension of the spring 52 will exert a pull on the wheel 48 so that the spoke 55 engaged with the wheel 36 will give a sudden forward rotary impulse to the drum, whereupon the next spoke will snap into the next

notch of the wheel. At the same time the spring 43 was brought under tension, by the movement of the gear 40 which brought 60 its lug 41 into engagement with one of the lugs 38. When the jerk is given by the spoked wheel, the spring 43 recoils and draws the wheel 36 forwardly so as to cause the partial rotation of the spoked 65 wheel, and the elevation of the advanced spoke out of the notch of the wheel. The rotation of the gear 40 is constant, so that it immediately engages its lug 41 with the lug 38 of the wheel 36, and continues the 70 forward driving of said wheel. Thus the drum is partially rotated, by the positive drive between the gears 21 and 40, and intermittently the drum is given a sudden 75 forward rotary impulse by the snapping of the adjacent spokes of the wheel 48 into two adjacent notches of the wheel 36. This motion causes the jostling of the seeds within the drum, and effects proper separation thereof, and the passage of certain seeds 80 through the openings of the inner cylinder, which are discharged onto the upper end of the chute, while the remainder of the seeds pass out through the lower end of the inner cylinder.

What is claimed is:

1. A driving means including a driven shaft, a peripherally notched wheel fixed on the driven shaft, a gear loosely mounted on the driven shaft, a spring connecting the wheel and gear, projections on the wheel and gear for causing positive driving connection therebetween, and a resiliently held member engaged in the notched wheel for imparting forward increased rotative impulses and stopping movements to the driven shaft.

2. A driving means including a driven shaft, a transverse shaft adjacent the driven shaft and having a driving gear thereon, a peripherally notched wheel fixed on the driven shaft, a gear loosely supported on the driven shaft outwardly of the wheel, spaced lugs on the wheel, a lug on the loose gear engaged between the spaced lugs for intermittent engagement therewith, a spring secured at its ends to the notched wheel and loose gear, and a spring pressed wheel having spokes engaged in the notches of the notched wheel, the driving gear 100 meshing with the loose gear.

In testimony whereof, I affix my signature.

NAFORD B. SANDVIG.
